UNITED STATES PATENT OFFICE.

MARION E. WATTS, OF PORTLAND, OREGON.

EXCAVATOR.

Application filed May 23, 1921. Serial No. 471,650.

To all whom it may concern:

Be it known that I, MARION E. WATTS, a citizen of the United States, residing at Portland, in the county of Multnomah and State of Oregon, have invented a new and useful Excavator, of which the following is a specification.

This invention relates to excavating machines, and more particularly to an excavating machine having an adjustable boom, whereby the digging elements which operate thereover, may be moved to various locations within a given radius, thereby eliminating the necessity of moving the machine to vary the angle of operation of the digging element.

A further object of the invention is to provide endless means associated with the digging elements, for delivering the excavated material to a position remote from the path of travel of the machine.

A still further object of the invention is to provide a hollow mast for supporting the boom, and at the same time providing a housing for the gearing employed in operating the boom.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:—

Figure 1 is a side elevational view of an excavating machine constructed in accordance with the present invention.

Figure 2 is a plan view of the same.

Figure 3 is a front elevational view of the machine, the adjustable boom being removed.

Figure 4 is a sectional view taken on line 4—4 of Figure 5.

Figure 5 is a sectional view taken on line 5—5 of Figure 2.

Figure 6 is a sectional view taken approximately on line 6—6 of Figure 2, and

Fig. 7 is a view of the upper end of the vertical shaft.

Referring to the drawings in detail, the machine includes a frame 5 which is supported at its rear, by means of the wheels 6, mounted on the axle 7, the forward portion 55 of the machine being mounted on the creepers 8, which are of any conventional construction, and which are secured to the frame in the usual manner.

Supported at the forward end of the machine is a hollow mast 9 which includes a base 10 and an upper movable section 11, the lower end of the upper movable section 11 being provided with a gear 12 formed exteriorly thereof, which gear is in mesh with the worm 13, which is supported adjacent to the lower end of the mast.

Extending through the mast is a vertical shaft 14 which is mounted in the bearings 15 and 16 respectively, disposed at opposite ends of the mast, the lower end of the shaft 14 having the beveled gear 17 mounted thereon, which beveled pinion is in mesh with the beveled pinions 18 and 19, carried by the shafts 20 and 21 respectively. The 75 main or drive shaft extends into the mast and carries the beveled gear 22 on one end thereof, which beveled gear meshes with the beveled gear 17 to transmit motion thereto, to accomplish the rotation of the shaft 14. 80 The shafts 20 and 21 extend laterally with respect to the mast, and have their outer extremities mounted in the bearings 23 which are supported by the frame. Mounted on one end of each of the shafts 20 and 21 is a 85 beveled pinion 24 which has connection with the clutch face 25 that cooperates with the clutch face 26, designed to move longitudinally of the shaft associated therewith for clutching the pinion 24 to its shaft. Dis- 90 posed at the end of each of the shafts 20 and 21 is a vertical shaft 27 which carries a beveled pinion 28 meshing with the beveled pinion 24, the pinion 28 also meshing with the beveled pinion 29 carried by the 95 shaft 30, and which is journaled in the bearing 31. The shaft 27 extends upwardly and has a pinion 32 secured thereto, which pinion 32 meshes with a suitable pinion 34 on one end of the shaft 33, which shaft 33 provides a support for the roller 38, over which the flexible conveyor 35 operates, it being

obvious that due to the meshing of the pinions and operation of the shafts as described, that rotary movement is imparted to the flexible conveyor 35.

5 Supported on the shaft 30 is a suitable roller 36 over which operates the flexible conveyor 37 which is designed to receive material from the flexible conveyor 35 and deliver the same rearwardly, or remote from 10 the path of travel of the machine while in operation. While this structure is described at one side of the machine, it is to be understood that this structure is duplicated at the opposite side of the machine, as shown by 15 Figure 2 of the drawings whereby the material may be delivered to either side of the machine, as desired.

The upper end of the shaft 14 is supported in the bearing 16 which is disposed 20 at the upper end of the mast, there being provided a beveled gear 39 supported on the extreme upper end of the shaft 14, to mesh with the beveled gear 40 which is secured to the shaft 41 and disposed at a point 25 intermediate the ends thereof. Supported on the outer ends of the shaft 41, are the sprocket wheels 42, which sprocket wheels accommodate over the chains 43 that also operate over the sprocket wheels 44 mounted on 30 the shaft 45 so that movement of the shaft 41 will be imparted to the shaft 45.

This shaft 45 is mounted at the upper end of the adjustable boom 46, which boom provides a support for the endless chain 47 that 35 carries the digging buckets 48, there being provided sprocket wheels 49 and 50 disposed adjacent to the ends of the bucket boom 46, to accommodate the endless chain 47 to accomplish the digging operation.

40 The sprockets 49 are mounted on the shaft 45 and receive rotary motion therefrom, whereby the buckets 48 are forced into their work. The bucket boom 46 is supported by the arms 51, that have connection with the 45 arms 52 at the lower ends thereof, the latter arms having pivotal connection with the vertical support 53 as through the arms 54, there being provided intermediate bracing bars 55 which connect the arms 51 and 52 50 to the upper portion of the mast.

An upper bracing bar 56 has connection with the outer or free end of the arm 51, and also has connection with the arms 57 that are supported adjacent to the upper 55 end of the frame 58, thereby bracing the upper portion of the boom support. This frame 58 embodies spaced arms 58', the lower ends thereof extending downwardly and having connection with the frame of the 60 machine as shown by Figure 3 of the drawings, the frame being indicated at 59'. The upper ends of the spaced arms 58' are held in such spaced relation as by means of the bar 64. Disposed adjacent to the upper ends

of the arm 51 are the pulleys 59 over which operate the cable 60 that extends downwardly and operates over the pulleys 61 that are connected to the bucket boom as through the medium of the arms 62, the intermediate portion of the cable operating over the pulleys 62'. The cable 60 also operates over the pulleys 63 supported by the upper bar 64 of the frame 58, from where the ends of the cable moves over the pulleys 65 and are wound on the drums 66, which drums are operated by suitable gearing to be hereinafter more fully described. From the foregoing it will be seen that by winding the cables on their drums, the bucket boom 46 may be adjusted vertically, to cause the buckets to operate at various angles with respect to the machine.

Supported in front of the mast 9 is a guard 67 that is supported by means of the bars 55 and the relatively short bars 68, the forward portion of the guard being open to permit the buckets 48 to pass therethrough and deliver material within the guard.

Disposed in direct alignment with the lower end of the guard 67 is a hopper 69 that is provided with discharge spouts 70 and 71, which extend laterally, one spout being located to deposit material on one of the flexible conveyors 35 while the opposite spout is disposed to deposit material on the opposed flexible conveyor 35 which operates at the opposite side of the machine, there being provided a pivoted gate 72 operating between the spouts, for controlling the passage of material therethrough, that is to say that when the gate 72 is moved to a position as indicated by Figure 3 of the drawings, material will be permitted to pass through the spout 70, but if the gate 72 is moved to the opposite side, material will be directed through the spout 71.

Mounted at the rear of the frame is a power device 73 which may be of any suitable character, the same in the present showing being in the form of an internal combustion engine, the drive shaft 74 thereof being shown as clutched to the main or drive shaft 75 of the machine through the clutch member 76, so that the shaft 75 may be operated idle at the will of the operator.

This drive shaft 75 is mounted in the bearings 77 and 78 and carries a pinion 79 adjacent to one end thereof, which pinion is constantly in mesh with the pinions 80 and 81 mounted on the shafts 82 and 83 respectively, which shafts also support the pinions 84. Friction clutch members 85 and 86 are mounted on the shafts 82 and 83, and it will be seen that due to the location of these clutch members 85 and 86, either of the shafts 82 and 83 may be thrown into operation at the will of the operator, the clutch members being however connected

with the gears 80 and 81 that are free to rotate on their shafts.

Mounted on one end of the shaft 83 is a beveled pinion 87 meshing with the beveled pinion 88 mounted on one end of the shaft 89, and which is clutched to the shaft by means of the clutch member 90 to impart rotary movement to the gear wheel 91, which in turn transmits motion to the relatively large gear wheel 92 mounted on the main or drive axle of the machine, which accomplishes the operation of the creepers to move the machine.

Supported in a plane above the shaft 82 is a shaft 117 which carries the gear 116 that meshes with the gear 118 also supported on the shaft 82, the shaft 117 carrying a worm 119 meshing with the gear 120 that is mounted on shaft 89.

A rectangular frame 93 is supported by the frame of the machine and one end of the drive shaft 75 terminates within the frame 93, where the same is provided with a clutch face to be clutched to the clutch face 94 of the stub shaft 95. Mounted on the stub shaft 95 is a beveled gear 96 which is constantly in mesh with the beveled gears 97 and 98, the gear 97 being mounted on one end of the shaft 99 that carries a beveled pinion 100 on the opposite end thereof, the latter pinion meshing with the pinions 101 and 102 there being mounted a clutch element 103 between the pinion 100 and gear 97, so that the pinion 100 may be thrown into and out of mesh at the will of the operator.

The pinion 101 imparts rotary movement to the shaft 104 which in turn imparts rotary movement to the pinion 105 through the pinion 106 mounted on one end of the shaft 104, the pinion 105 operating to impart rotary movement to the shaft 107, to which the worm 13 is keyed. Thus it will be seen that rotary movement is imparted to the mast 9 through the train of gears, as described. The pinion 98 is mounted on one end of the shaft 108 and imparts rotary movement thereto, which shaft imparts rotary movement to the beveled pinion 109 through the clutch element 110, which in turn transmits rotary motion to the pinion 111 that is mounted on one end of the shaft 112 that carries a worm meshing with the gear 113.

The gear 113 is mounted on one end of the shaft 114 and on which shaft the drums 115 are mounted, the cable 60 being wound thereon. If it is desired to rotate the drums to raise or lower the bucket boom, the clutch member 110 should be operated to throw the pinion 100 into operation to accomplish the rotation of the shaft 114, and drums as described.

If it is desired to rotate the mast, to cause the bucket boom to operate at various angles

with respect to the machine proper, it is only necessary to operate the clutch member 103 which operation throws the pinion 101 into operation which imparts rotary movement to the shaft 107, its worm gear 13, and the gear 12 mounted at the lower end of the movable portion 11 of the mast 9.

It might be further stated however that the direction of rotation should be governed by the direction of rotation of the drive shaft in any well known manner.

In the operation of the device, if it is desired to operate the buckets, the clutch mechanisms are operated to move the drive shaft 75 into engagement with the shaft 95, which carries the pinion 22, and since the pinion 22 meshes with the beveled gear 17, the shaft 14 is operated, transmitting motion to the pinion carried at the upper end thereof, which pinion rotates the shaft 41, sprocket wheels 42 and 44, through the medium of the chains, which in turn imparts the rotary movement to the buckets.

If it is desired to change the angle of operation, of the bucket boom, suitable gearing is operated to cause the rotation of the shaft 107 and worm 13 to rotate the movable mast as previously described.

Having thus described the invention, what is claimed as new is:

1. An excavating machine comprising a frame, a hollow mast supported at one end of the frame, means for rotating the mast in a horizontal plane, an operating shaft extending through the mast and having beveled pinions formed on the ends thereof, a bucket boom having pivotal connection with the mast, buckets operating over the boom, means associated with the beveled pinions on one end of the operating shaft for operating the buckets, means for moving the bucket boom vertically, and means for delivering material laterally of the machine.

2. An excavating machine comprising a frame, a hollow mast supported at one end of the frame, a movable bucket boom supported by the mast, a hopper supported by the hollow mast, a guard supported at the front of the mast directly over the hopper to direct material to the hopper, means disposed under the hopper for receiving material therefrom and delivering the same laterally of the frame, an endless chain of buckets operating on the bucket boom, and means passing through the hollow mast for controlling the movements of the boom.

3. An excavating machine comprising a movable frame, a hollow mast supported by the frame, a boom supported by the mast, a shaft extending through the hollow mast and carrying a pinion at the lower end thereof, shafts extending through the base of the mast, and carrying pinions in mesh with the pinion on the shaft that extends through

the hollow mast, to rotate the same, a hopper movable with the hollow mast, an endless chain of buckets operating over the boom and adapted to deliver material to the hopper, and means under the hopper for delivering material laterally.

5 In testimony that I claim the foregoing

as my own, I have hereto affixed my signature in the presence of two witnesses.

MARION E. WATTS.
